UNITED STATES PATENT OFFICE

2,441,070

HIGH LIFT LOADER

Daniel S. Hoover, Mansfield, Ohio

Application June 21, 1946, Serial No. 678,340

3 Claims. (CL 214—140)

1

This invention relates to a high lift loader, and has for one of its objects the production of a simple and efficient means for lifting a load to a sufficient height to dump the load into a truck, and then moving or swinging the frame forwardly to a dumping position without backing the supporting tractor away from the truck.

A further object of this invention is the production of a simple and efficient means for tilting the scoop to adjust the angle of the cutting edge thereof.

Other objects and advantages of the present invention will appear throughout the following specification and claims.

In the drawings:

Figure 1 is a side elevational view of the loader, the supporting tractor being shown in dotted lines;

Figure 2 is a side elevational view showing the scoop in an elevated position;

Figure 3 is a front elevational view;

Figure 4 is a front elevational view with certain parts shown in section, and the scoop being removed;

Figure 5 is a perspective view of the scoop;

Figure 6 is a transverse sectional view through one of the vertical frame members;

Figure 7 is a fragmentary longitudinal sectional view through the scoop.

By referring to the drawings, it will be seen that 10 designates the tractor-engaging yoke which is secured to and extends along the sides and across the front of the tractor 11, the tractor being shown in dotted lines. A pair of supporting links 12 constituting hangers are pivoted to the yoke 10, as at 13, each link 12 being pivoted upon opposite sides of the yoke. A vertical frame member 14 is pivoted to the forward end of each link 12, the frame members extending in substantially parallel relation in an upward direction. Each frame member 14 is U-shaped in cross-section with the channel thereof facing forwardly, as shown in Figure 3.

A scoop-lifting frame 15 is carried by the vertical frame 14 and comprises a pair of parallel lifting arms 16 which are pivotally secured to the upper ends of the frame members 14. These arms 16 are inclined rearwardly at their upper ends and are connected by means of a transverse portion 18. A flexible bridle or check chain 19 of any suitable type is secured to this transverse portion 18 at one end and is anchored to the tractor 11, as at 20.

A brace strap 21 ties the upper ends of the frame members 14 together, and a forwardly ex-

2

tending bracket 22 is carried intermediate the ends of the strap 21. A bracket 23 is also hung from the front of the yoke 10 and depends therefrom. A hydraulic lift cylinder 24 of the conventional type is pivotally secured to the bracket 23 at its lower end and the plunger rod 25 of the cylinder 24 is pivotally secured to the bracket 21, as shown in Figures 1 and 4. A hydraulic jack or cylinder 26, of the conventional type, is interposed between the link 12 and the frame member 14, as shown in Figure 1, and a similar arrangement may be provided on each side of the apparatus between each link 12 and frame member 14, to swing the frame members 14 forwardly or rearwardly.

Each lifting arm 16 is provided with a forwardly extending lower end 27 and a lifting scoop 28 is pivotally secured to the ends 27 of the arms 16, as at 29. The scoop 28 is preferably provided with a central partition 30. The plunger rod 31 of the hydraulic cylinder 32 is adjustably connected to the scoop 28, as at 28a. This cylinder 32 is pivotally connected to the bracket 22, as at 33. As the rod 31 is extended in the cylinder 32 in the conventional manner, the scoop 28 will be swung on its pivots 29 to a dumping position, as shown in Figure 2. The scoop 28 is provided with a suitable forward cutting edge or blade 34 and the tilt of the scoop 28 may be selectively regulated by moving the plunger rod 31 into and out of the cylinder 32 to adjust the depth of cut of the blade 34.

It should be understood that the hydraulic cylinders 24, 26 and 32 are of the conventional type which may be operated from a control station 35 of the conventional type which is connected to the hydraulic cylinders in any conventional manner. The particular type of hydraulic cylinder and the operating means therefor form no part of the present invention, and this particular structure may be modified without departing from the spirit of the invention.

The operation of the loader is as follows:

The tractor 11 is moved to a position to scoop up the load, and the scoop 28 is tilted to cause the blade 34 to dig into the material to be loaded. The scoop is tilted to the desired position by means of the hydraulic cylinder 32. The frame members 14 and the links 12 are raised to the desired elevation by means of the hydraulic cylinder 24 which is anchored at its lower end to the bracket 23 and at its upper end to the bracket 22. As the plunger rod 25 is extended the links 12 will swing upwardly thereby lifting the frame member 14 to the position shown in Figure 2. The scoop-lifting

frame 18 will also be swung upwardly and outwardly to the position shown in Figure 2, because of the fact that the chain 19 holds the transverse portion 18 thereof in an anchored position.

After the scoop 28 has been raised to the position shown in full line in Figure 2, the cylinder 26 is operated to swing the frame members 14 forwardly to the dotted line position shown in Figure 2 thereby causing the scoop to be bodily shifted forwardly. When the scoop 28 reaches this forward position, the scoop is tilted to a dumping position shown in dotted lines in Figure 2 by operating the hydraulic cylinder 32.

It should be understood that the loader first scoops up the load, then elevates the load, then shifts the load forwardly and then dumps the load from the elevated shifted position. It should be further understood that certain detail changes may be made in the structure illustrated without departing from the spirit of the invention, so long as these changes fall within the scope of the appended claims.

Having described the invention, what is claimed is:

1. A loader of the class described comprising a support, a hanger pivoted to said support, a forwardly swinging vertical frame pivoted at its lower end to said hanger, a scoop-lifting frame hinged at the upper end of said vertical frame and anchored at its opposite end to said support, means tied to one end of said scoop-lifting frame for limiting the swinging of said scoop-lifting frame in one direction and adapted to elevate the outer end of said scoop-lifting frame as said vertical frame is swung forwardly, a hinged scoop carried by the outer end of said scoop-lifting frame, means for lifting the vertical frame and simultaneously and automatically swinging the scoop of the scoop-lifting frame upwardly, means for swinging the vertical frame forwardly, and means for tilting said scoop to a dumping position.

2. A loader of the class described comprising a support, a hanger pivoted to said support, a forwardly swinging vertical frame pivoted at its lower end to said hanger, a scoop-lifting frame hinged at the upper end of said vertical frame,

means tied to one end of said scoop-lifting frame for limiting the swinging of said scoop-lifting frame in one direction and adapted to elevate the outer end of said scoop-lifting frame as said vertical frame is swung forwardly, a hinged scoop carried by the outer end of said scoop-lifting frame, means for lifting the vertical frame and simultaneously and automatically swinging the scoop of the scoop-lifting frame upwardly, means for swinging the vertical frame forwardly, means for tilting said scoop to a dumping position, said vertical frame comprising a plurality of channel members, and said scoop-lifting frame comprising a plurality of arms fitting longitudinally within said channel members when the scoop is in a loading position to resist lateral strain upon said arms.

3. A loader of the class described comprising a support, a frame hinged upon said support for upward swinging movement upon said support, means for swinging said frame forwardly, a scoop-lifting frame hingedly mounted upon said first mentioned frame for automatic upward swinging movement as the first mentioned frame is swung forwardly, a scoop hinged to the outer end of said scoop-lifting frame, means for tilting the scoop to a dumping position, and bracing means carried by the first mentioned frame and engaging and bracing the scoop-lifting frame at a point beyond its mounting upon the first mentioned frame when the scoop-lifting frame is in a loading position to resist lateral strain upon said scoop-lifting frame.
